UNITED STATES PATENT OFFICE.

ERMINIO FERRARIS, OF MONTEPONI, SARDINIA, ITALY, ASSIGNOR OF ONE-FOURTH TO WALTER RENTON INGALLS, OF LYNN, MASSACHUSETTS.

FURNACE.

SPECIFICATION forming part of Letters Patent No. 714,685, dated December 2, 1902.

Application filed August 16, 1901. Serial No. 72,249. (No model.)

To all whom it may concern:

Be it known that I, ERMINIO FERRARIS, a subject of the King of Italy, residing at Monteponi, Sardinia, Italy, have invented certain new and useful Improvements in Furnaces Adapted for the Heating of Retorts for Zinc Distillation and other Purposes, (for which application has been made for Letters Patent in Italy in the name of the Societa di Monteponi, No. 16,263, dated July 26, 1901,) of which the following is a specification.

The object of the present invention is to diminish the consumption of fuel and to equalize the temperature of retort-furnaces heated by gas for the distillation of zinc from its ores.

The accompanying drawings represent a double furnace.

Figure 1 shows a longitudinal section on the irregular lines 1, 2, 3, and 4 of Fig. 3; Fig. 2, a transverse section on the irregular lines 5, 6, 7, and 8 of Fig. 3, Fig. 3 showing a horizontal section through a half of the combustion-chambers, a horizontal section through one recuperative chamber, and a horizontal section through flue leading from the recuperative chamber.

Like letters indicate like parts throughout the drawings.

The furnace may be single instead of double, as shown in the drawings, without altering the system.

The chambers A of the furnace contain each three series of oval retorts a. It could just as well be provided with a greater number of series of retorts of a different shape—for example, with round Belgian retorts. The combustible gases produced by generators or coming from any other suitable source arrive at the furnace through the pipe B and pass the butterfly-valve b, which sends them to the right or to the left alternately. According to the arrows in the drawings the gas is directed to the right; but by reversing the valve the gas can be directed to the left, so as to follow a course exactly similar with the one about to be described. The gas traverses the flues c and d between the two furnaces, and it enters into the retort-chambers through openings e underneath the retorts between each vertical series, with the exception of some of the center series, where the holes are closed.

The construction of the gas-conducting flues c d in the masonry of the furnace not only preserves the initial heat of the gas, but also enables it to become further preheated by abstraction of heat from the combustion-chambers of the furnace.

The retort-furnaces are of uniform section and can be constructed of any desired length. At the center of the length of the furnace a partition-wall f cuts off the part of the lower retort-chamber at the lower horizontal series in order to cause the gas to spread between the series of the retorts.

The air required for combustion enters through the valve C, (which may be of a conventional type,) traverses the flues g and h, the two sections m n of the recuperators D, and passes into the retort-chambers at their extreme end on the right through the openings in the vaulting of the recuperators, which correspond with the opening o' shown on the left-hand side of Figs. 1 and 3.

The air spreads in the retort-chambers, where it meets the gas which enters through the openings e. The flames extend along all the retorts from right to left, and the products of combustion, drawn by a chimney which communicates with the valve C, descend through the openings o' into the recuperators D', in accordance with the arrows of the drawings, pass through the flues h' and g', and by reason of the position of the valve C pass to the flue i of the chimney. (Not shown in the drawings.)

The recuperators are filled with perforated or stacked bricks, which form or afford horizontal passages having no communication one with the other, and a partition l divides each generator into two unequal sections, the larger and hotter of which n n' extends to the vaulting which separates the recuperator from the retort-chamber, and the other colder chamber m or m' is above the flues h h', respectively. The two compartments are traversed in the opposite direction either by air which enters at the furnace or by the products of combustion passing to the chimney.

In order to obtain an equal temperature in all the retort-chambers, the gas and air valves B and C, respectively, are reversed at equal intervals.

In order to avoid mistakes, rods *v w* of the two valves are connected together by a set of levers and chains *x y z*.

What I claim as my invention, and desire 5 to secure by Letters Patent, is—

1. A furnace comprising a combustion-chamber and an overhead gas-inlet, arranged to introduce gas at a point intermediate between the ends of the furnace, and flues, ducts or passages constructed in the masonry of the furnace arranged to conduct the gas in opposite directions from the inlet to the combustion-chamber, and means for delivering the inflowing gas into one or the other of the 15 flues, ducts or passages, which flues, ducts or passages are traversed solely by the combustible gas, as described, and for the purpose specified.

2. A furnace comprising a combustion-chamber and an overhead gas-inlet, arranged at substantially the center of the length of the furnace, and flues, ducts or passages constructed in the masonry of the furnace arranged to conduct the gas in opposite directions from the inlet to the combustion-chamber, and means for diverting the inflowing gas into one or the other of the flues, ducts or passages, which flues, ducts or passages are traversed solely by the combustible gas, 30 as described, and for the purpose specified.

3. A furnace comprising a combustion-chamber and a gas-inlet, arranged to introduce gas at a point intermediate between the ends of the furnace, and flues, ducts or passages arranged to conduct the gas in opposite directions from the inlet to the combustion-chamber, said flues, ducts or passages communicating with ports which lead into the combustion-chamber, and which are arranged 35 at intervals in the length of said combustion-chamber, on either side of a line extending transversely through the middle of the furnace, and means for diverting the inflowing gas into one or the other of the flues, ducts or 40 passages, which flues, ducts or passages are traversed solely by the combustible gas.

4. A furnace comprising a combustion-chamber and an overhead gas-inlet, arranged to introduce gas at a point intermediate between the ends of the furnace, and flues, ducts or passages constructed in the masonry of the furnace arranged to conduct the gas in opposite directions from the inlet to the combustion-chamber, and means for diverting the inflowing gas into one or the other of the flues, ducts or 50 passages, which flues, ducts or passages are traversed solely by the combustible gas, together with regenerative chambers in communication with the combustion-chamber 55 at opposite ends of said combustion-chamber, and means for reversing the direction of flow of outgoing products of combustion and in-

coming air through the furnace, for the purpose specified.

5. A furnace comprising a combustion-chamber and an overhead gas-inlet, arranged to introduce gas at a point intermediate between the ends of the furnace, and flues, ducts or passages constructed in the masonry of the furnace arranged in connection with the said combustion-chamber and extending in the direction of the length thereof, being arranged to conduct the gas in opposite directions from the inlet to the combustion-chamber, and means for diverting the inflowing gas into one 75 or the other of the flues, ducts or passages, which flues, ducts or passages are traversed solely by the combustible gas, as described, and for the purpose specified.

6. A furnace comprising combustion-chambers and a gas-inlet, arranged to introduce gas at a point intermediate between the ends of the furnace, and flues, ducts or passages arranged in connection with the said combustion-chambers and extending in the direction 85 of the length thereof, being arranged to conduct the gas in opposite directions from the inlet to the combustion-chambers, said flues, ducts or passages communicating with ports which lead laterally into the combustion-chambers, and which are arranged at intervals in the length of said combustion-chambers, on either 90 side of a line extending transversely through the middle of the furnace, and means for diverting the inflowing gas into one or the other 95 of the flues, ducts or passages, which flues, ducts or passages are traversed solely by the combustible gas, for the purpose specified.

7. A furnace comprising a combustion-chamber, an overhead gas-inlet intermediate 100 between the ends of the furnace, and a number of regenerative chambers, together with means for diverting the course of the gas and the air for its combustion so that the gas and air are supplied alternately in portions of the 105 combustion-chamber lying on opposite sides of a transverse line extending through the middle of the furnace, and appropriate flues, ducts or passages constructed in the masonry of the furnace for conduction of the gas, and 110 regenerative chambers communicating with the said combustion-chamber at opposite ends thereof, said regenerative chambers being so arranged that the air and the products of combustion may traverse them alternately, substantially as described.

In testimony whereof I have signed my name to this specification in the presence of two subscribing witnesses.
